US00D770430S

(12) **United States Design Patent** (10) **Patent No.:** **US D770,430 S**
(45) **Date of Patent:** **** Nov. 1, 2016**

(54) **CORE FOR MOBILE PHONE**

(71) Applicant: **LG ELECTRONICS INC.**, Seoul (KR)

(72) Inventor: **Sungho Lee**, Seoul (KR)

(73) Assignee: **LG Electronics Inc.**, Seoul (KR)

(**) Term: **14 Years**

(21) Appl. No.: **29/504,803**

(22) Filed: **Oct. 9, 2014**

(30) **Foreign Application Priority Data**

Apr. 10, 2014 (KR) 30-2014-0018097

(51) **LOC (10) Cl.** **14-03**

(52) **U.S. Cl.**

USPC **D14/240**

(57) **CLAIM**

The ornamental design for a core for mobile phone, as shown and described.

DESCRIPTION

FIG. 1 is a perspective view of the core for mobile phone showing my new design;

FIG. 2 is a front view thereof;

FIG. 3 is a rear view thereof;

FIG. 4 is a left side view thereof where the right side view is a mirror image;

FIG. 5 is a top plan view thereof;

FIG. 6 is a bottom plan view thereof;

FIG. 7 is another front perspective view of the core for mobile phone, as shown in a first environment;

FIG. 8 is a rear perspective view of the core for mobile phone, as shown in the first environment;

FIG. 9 is another perspective view of the core for mobile phone, shown in a second environment;

FIG. 10 is another left side view of the core for mobile phone, shown in a third environment; and,

FIG. 11 is another perspective view of the core for mobile phone, shown in a fourth environment.

The broken lines are directed to environment; the broken lines form no part of the claimed design.

1 Claim, 10 Drawing Sheets
